(57) **CLAIM**

The ornamental design for a LED package, as shown and described.

DESCRIPTION

FIG. 1 is a top perspective view of an LED package according to an embodiment of the present invention.

FIG. 2 is a right elevation view of an LED package according to an embodiment of the present invention.

FIG. 3 is a left elevation view of an LED package according to an embodiment of the present invention.

FIG. 4 is a front elevation view of an LED package according to an embodiment of the present invention.

FIG. 5 is a rear elevation view of an LED package according to an embodiment of the present invention.

FIG. 6 is a top plan view of an LED package according to an embodiment of the present invention; and,

FIG. 7 is a bottom plan view of an LED package according to an embodiment of the present invention.

The features shown in broken lines in FIGS. 1-7 form no part of the claimed design in the embodiments shown.
